[57] CLAIM

The ornamental design for a vanity table, as shown and described.

DESCRIPTION

FIG. 1 is a front and left side perspective view of a vanity table showing my new design;

FIG. 2 is a right side elevational view thereof;

FIG. 3 is a top plan view thereof;

FIG. 4 is a front and right side perspective view showing a second embodiment of that shown in FIG. 1;

FIG. 5 is a front and left side elevational view showing a third embodiment of that shown in FIG. 1; and

FIG. 6 is a top plan view thereof.
